Company, Wadena, Minn., a corporation of Minnesota

Application September 17, 1953, Serial No. 26,841

Term of patent 7 years

(Cl. D15—1)

To all whom it may concern:

Be it known that we, Merton M. Bottemiller and Leonard B. Olsen, both citizens of the United States, residing respectively at Wadena, in the county of Wadena and State of Minnesota, and at Minneapolis, in the county of Hennepin and State of Minnesota, have invented a new, original, and ornamental Design for a Combined Hassock and Magazine Rack, of which the following is a specification, reference being made to the accompanying drawing, forming part thereof, and in which

The single figure is a perspective view of a combined

hassock and magazine rack revealing the side, end, and top thereof, embodying our new design.

We claim:

The ornamental design for a combined hassock and magazine rack, as shown.
